(57) **CLAIM**

The ornamental design for a combined bag/garment, as shown and described.

DESCRIPTION

FIG. 1 is a perspective view of the rear side of the combined bag/garment of my new design showing side flaps in an open configuration.

FIG. 2 is an elevational view of the front side of the combined bag/garment of my new design with side flaps in an open configuration.

FIG. 3 is a top plan view thereof.

FIG. 4 is an elevational view of the rear side thereof.

FIG. 5 is a bottom plan view thereof.

FIG. 6 is a left side elevational view thereof; and,

FIG. 7 is a right side elevational view thereof.

The broken lines showing is included for the purpose of illustrating environment of the article and forms no part of the claimed design.
